UNITED STATES PATENT OFFICE.

CLAIRES AVERY, OF NEW YORK, N. Y.

DESIGN FOR A DOLL.

47,180.

Specification for Design.

Patented Apr. 6, 1915.

Application filed December 9, 1914. Serial No. 876,376. Term of patent 7 years.

To all whom it may concern:

Be it known that I, CLAIRE AVERY, a citizen of the United States, and a resident of the city of New York, borough of Manhattan, in the county and State of New York, have invented a new, original, and ornamental Design for a Doll, of which the following is a specification, reference being had to the accompanying drawing, forming part thereof.

The figure is a perspective view of a doll showing my new design.

I claim:

The ornamental design for a doll as shown.

CLAIRES AVERY.

Witnesses:

THEO. G. HOSTER,
PHILIP D. ROLLHAUS.
